UNITED STATES PATENT OFFICE.

OSCAR E. CARLSON, OF DORCHESTER, MASSACHUSETTS.

SOOT CLEANER FOR LOCOMOTIVES.

Application filed March 30, 1922, Serial No. 548,000. Renewed September 19, 1928.

This invention relates to soot cleaners for locomotives of that type which comprises a nozzle or jet pipe which is normally received in a pocket formed in the water leg of the 5 boiler at the side of the fire-box but which may be projected from the pocket into the fire-box while steam is delivered therefrom into and through the flues for cleaning them.

One of the objects of the invention is to 10 provide an improved soot cleaner of this type in which the means for projecting the nozzle or jet pipe from the pocket into the fire-box and also the means for turning the jet pipe on its axis, are located in close proximity to 15 each other so that they can be easily manipulated.

Another object of the invention is to provide a soot cleaner having novel means for 20 turning the nozzle on its axis by which the movement of the nozzle can be accurately controlled, thus making it possible to thoroughly 25 clean all of the flues.

Other objects of my invention are to improve generally soot cleaners of this type all 30 as will be more fully hereinafter set forth.

In order to give an understanding of the invention I have illustrated in the drawings a selected embodiment thereof which will now 35 be described after which the novel features will be pointed out in the appended claims.

Fig. 1 is a fragmentary sectional view through a portion of a locomotive boiler showing my improved soot cleaner applied thereto.

Fig. 2 is an enlarged section on substantially the line 2—2, Fig. 1.

Fig. 3 is a section on the line 3—3, Fig. 4.

Fig. 4 is a view of the soot cleaner looking toward the right in Fig. 2 with a part broken 40 out to better show the construction.

Fig. 5 is a sectional view of one of the swivel joints.

In Fig. 1 of the drawings I have shown in 45 horizontal section a sufficient portion of the fire-box to enable my invention to be understood and in said figure, 1 indicates the barrel of the locomotive boiler which is provided with the combustion chamber 2 therein forwardly of which is the usual flue sheet 3 carrying one end of the flues 4 that lead into 50 the fire-box. At the side of the fire-box is the usual water leg 5 formed between the inner and outer sheets 6 and 7 and this water leg extends around to the front of the fire-box. 55 The door or opening leading to the combustion chamber is indicated at 8, and 90 indi-

cates in section the wall of the cab. It will be understood that Fig. 1 is intended to indicate a horizontal section through the fire-box of the boiler.

My improved soot cleaner is of the familiar type which embodies a jet nozzle 9 having a jet opening 10 therein through which steam is adapted to be delivered against the flue sheet 3 for blowing out the flues. This jet nozzle 65 is normally confined within a pocket 11 formed in the water leg 5, said pocket being herein shown as constituted by a tube 12 extending across the space between the sheets 6 and 7. This jet nozzle 9 is arranged to be 70 withdrawn into the pocket as shown in dotted lines Fig. 3 when it is not in use, and to be projected into the fire-box as shown in Fig. 1 and in full lines Fig. 3 when it is to be used 75 for cleaning the flues, and my invention relates to novel means for manipulating the nozzle to project it into the fire-box and then to turn it about its axis so that the steam issuing therefrom will be directed toward any horizontal row of flues.

Secured to the outside sheet 7 is a fitting or casing 13 having a steam passage 14 leading to a chamber 15. A steam pipe 16 leads into the passage 14, said steam pipe communicating with a steam boiler or other suitable 85 source of supply.

The nozzle 9 has a hollow stem or pipe 17 extending into the chamber 15 and provided with ports 18 which communicate with the chamber when the nozzle is projected. The 90 chamber 15 has an extension 19 at its rear end into which the ported end of the stem 17 is received when the nozzle is retracted, and this chamber is of a size to fit the stem so that when the nozzle is retracted, as shown in 95 dotted lines the ports are closed by the walls of the chamber extension 19 thus shutting off steam from the nozzle. The stem is formed with the shoulder 22 which seats against the inner wall 23 of the chamber extension 19 100 when the nozzle is retracted thereby assisting in preventing leakage of steam past the stem.

The stem or pipe 17 is extended or provided with an extension 20 which projects beyond the fitting 13, the latter being provided with a stuffing box 21 to form a tight joint.

The means for projecting the nozzle into the fire-box and also for turning the stem are connected to the end of the stem extension 20. 110

The fitting 13 is shown as having a rock shaft 24 journaled therein which is pro-

vided with two arms 25 situated at either side of the fitting. These arms have links 26 pivotally connected thereto at 27, said links in turn being pivoted to a collar or 5 yoke 28 which is swivelled on the end of the stem extension 20. Said collar 28 is shown as loosely mounted on a sleeve 29 which is fast to the extension. The turning of the rock shaft 24 from the position shown in 10 Fig. 2 to that shown in Fig. 3 will operate through the arms 25 and links 26 to project the nozzle as will be readily understood. This rock shaft 24 extends parallel to the side of the boiler and is provided with a 15 tubular extension 30 that extends into the cab 90, said extension having a lever 31 at its end by which the shaft may be turned. This lever is in convenient position for the engineer or fireman to manipulate and by turning 20 the lever in one direction the nozzle will be projected into the fire-box and by turning it in the other direction the nozzle will be retracted.

For turning the nozzle about its axis to 25 direct the steam jet up and down the front of the flue sheet, I have provided a construction involving a hand wheel which is associated with the lever 31 and is in convenient position for the fireman or engineer to manipulate.

Extending transversely through the end of the stem extension 20 is an arm 32 by which the nozzle may be turned about its axis and this arm is operated from a hand wheel 33 30 that is associated with the lever 31. This hand wheel is fast on the end of a rod 34 that extends axially of the tubular member 30 and is provided with a screw-threaded portion 35 that threads into a nut 36 slidably mounted 40 in the tube 30. The nut is provided with an ear 37 extending laterally through a slot 38 in the tube and this ear is pivotally connected to the arm 32 by means of a jointed link 39.

The lever 31 is provided with a cap-shaped 45 head 40 which fits over the end of the tube 30 and is rigid therewith and the rod 34 extends through and finds bearing in said cap 40. Said rod is held from longitudinal movement by a collar 41 fast thereon and engaging the 50 inner side of the cap and also by the engagement of the hand wheel 33 with the outside of the cap.

With this arrangement it will be observed 55 that the turning of the hand wheel 33 will move the nut 36 back and forth in the tube 30, such movement being communicated through the link 39 to the arm 32 and thereby turning the nozzle about its axis.

Inasmuch as the tube 30 is turned to move 60 the nozzle into and out of operative position, it is necessary to provide a flexible connection between the ear 37 and the arm 32, and this is accomplished by making the link 39 in sections which are jointed together. One section 65 is shown at 42 and it is pivoted to the ear 37

and also pivoted at 43 to one end of the central section 44 pivoted to the opposite end of the central section and also pivoted to the inturned end 45 of the arm 70 32. This allows for the turning movement of the tube 30 without cramping the connection between the nut and the arm 32.

I will preferably provide a flexible connection between the rock shaft 24 and the tube 75 30 so as to avoid any binding or cramping of the parts. Such a connection is shown in Fig. 5 wherein the tube 30 has a tubular head 46 at one end which is pivotally connected to the rock shaft 24 by means of a 80 connection somewhat on the order of a universal joint. This connection comprises a pivot pin 47 carried by the head 46 and extending through the end of the rock shaft 24, said pin being larger at its center than 85 near its ends and the end of the rock shaft 24 having the rounded faces 48 to permit of a rocking movement.

The operation of the device will be readily understood from the foregoing. When it is 90 desired to clean the flues the operator will manipulate the lever 31 thereby turning the tube 30 and rock shaft 24 and projecting the nozzle 9 into the fire-box. The operator then manipulates the hand wheel 33 and by so 95 doing the nozzle is turned on its axis so that the steam issuing therefrom may be directed into the flues of any horizontal row. Since the axial turning movement of the nozzle is accomplished through the screw 35 and nut 100 36 a perfect control of the nozzle is possible and the steam may be accurately directed to any line of flues.

In order to provide for holding the nozzle 9 in its retracted position I make the arms 25 and links 26 so that they will automatically 105 lock the nozzle in such retracted position. One of the arms 25 is provided with a stop pin 49 and the corresponding link 26 is extended beyond the pivot 27 and is provided with a notch 50 to receive the pin when the parts are in the position shown in Fig. 2. This notch is of such a depth that the pivot pin 27 can be carried slightly by the center 110 thus locking the nozzle from forward movement except by the positive downward swinging movement of the arm 25.

While I have illustrated herein a selected embodiment of the invention I do not wish 115 to be limited to the constructional features shown.

I claim:

1. In a locomotive soot cleaner for use in a locomotive fire-box provided with a combustion chamber, a water leg at the side of the fire-box provided with a pocket communicating with the combustion chamber, and a flue sheet, the combination with said pocket, of a jet nozzle therein, a rock shaft connected to the nozzle for projecting it into the com- 120 125 130

bustion chamber, a tubular extension on the rock shaft, and means situated within said extension and operatively connected to the nozzle to turn the latter about its axis.

5. 2. In a locomotive soot cleaner for use in a locomotive fire-box provided with a combustion chamber, a water leg at the side of the fire-box provided with a pocket communicating with the combustion chamber, and a flue sheet, the combination with said pocket, of a jet nozzle therein, a rock shaft connected to the nozzle for projecting it into the combustion chamber, said rock shaft having a slotted tubular extension, a nut in said extension having an ear projecting through said slot, an operating screw situated axially of the tubular extension and having screw-threaded engagement with said nut, and operative connections between the ear and the nozzle whereby movement of the nut longitudinally of the tubular extension operates to turn the nozzle about its axis.

3. In a boiler tube cleaner, a casing, a steam chamber therein, a blower nozzle stem passing through said chamber, a yoke pivotally mounted on the outer end of the stem, a shaft journaled in the casing, arms rigid with said shaft, link connections between said yoke and arms, and means for rotating said stem independently of said yoke.

4. A locomotive engine having a fire tube boiler, a combustion chamber defined in part by the boiler tube sheet, an engine cab, a tube cleaner adapted to discharge into the combustion chamber toward said sheet and comprising a blower member having an inlet opening, a casing in which said blower member is movably mounted, a pressure supply chamber in said casing, and means for moving said blower member longitudinally of the casing for bringing the inlet opening into register with said pressure supply chamber, said means, including a yoke, pivotally mounted with respect to said casing and in swiveling engagement with said blower member, and independently movable means for rotating said blower member.

5. In a locomotive soot cleaner for use in a locomotive fire-box provided with a combustion chamber, a water leg at the side of the fire-box provided with a pocket communicating with the combustion chamber, and a flue

sheet, the combination with said pocket, of a jet nozzle therein, a rock-shaft mounted to rotate about its axis and connected to the nozzle for projecting it into the combustion chamber, and means extending substantially parallel with said shaft and operatively connected to the nozzle and adapted to turn the latter about its axis.

6. In a locomotive soot cleaner for use in a locomotive having a cab, a fire-box provided with a combustion chamber, a water leg at the side of the fire-box provided with a pocket communicating with the combustion chamber, and a flue sheet, the combination with said pocket and cab, of a jet nozzle in the pocket, a rock shaft mounted in stationary bearings and turnable about an axis extending parallel to the fire-box, said rock shaft extending into the cab, connections between the rock shaft and the nozzle whereby turning movement of the rock shaft about its axis projects the nozzle into the fire-box, a member extending longitudinally of the rock shaft and having a part movable in the direction of the axis of said shaft, and an operative connection between said member and the nozzle by which movement of the member turns the nozzle on its axis, said connection being operative in any angular position of the rock shaft.

7. In combination, a locomotive boiler, a fire box therein, a tube extending through the walls of the boiler into the fire box, a tube cleaner mounted on said boiler in said tube and arranged to discharge into the fire box and formed with a blower member having an inlet opening, a casing in which said blower member is movably mounted, said casing being formed with a pressure supply chamber therein, means for moving said blower member longitudinally with respect to said casing for connecting its inlet opening with the pressure supply chamber of the casing, said means comprising a member in swivelling engagement with said blower member, actuating means for said blower member movably connected to said swivelling member, and independently movable means for rotating said blower member.

In testimony whereof, I have signed my name to this specification.

OSCAR E. CARLSON.
